Edward F. Huntge, of New York, N.Y.

Letters Patent No. 3018-Dated Jan'y 17-1865.

Design for a Statuette.

The schedule referred to in the letters Patent and making part of the same.

That is to say concerning

It is known that Edward F. Huntge, of the City of New York, County and State of New York, have invented or produced a new and original design ~~with himself, and do hereby declare that the following is a full and exact description of the same.~~

Statuette of

Wolfgang von Goethe

The figure of Goethe dressed in the costume of the latter part of the 18th century with a cloak suspended from the right shoulder, the folds of which are gathered by his right hand, which rests on his hip. His left arm rests upon a gothic iron with a sword of Margarethe and a little child holding pattern leaves. The hand grasps a manuscript of Faust. He is represented in the age of 35, all of which are clearly seen in the accompanying Photographs.

What is to my inscription or production and desire to secure by letters Patent is The design for Statuette of Goethe as shown and described.
